UNITED STATES PATENT OFFICE.

GUSTAV PROCHAZKA, OF NEW YORK, N. Y., ASSIGNOR OF ONE-HALF TO FRANK BRODSKY, OF NEW YORK, N. Y.

ENGINE.

1,102,952.

Specification of Letters Patent.

Patented July 7, 1914.

Application filed August 8, 1913. Serial No. 783,795.

To all whom it may concern:

Be it known that I, GUSTAV PROCHAZKA, a subject of the Emperor of Austria-Hungary, and a resident of the city of New York, borough of Brooklyn, in the county of Kings and State of New York, have invented a new and Improved Engine, of which the following is a full, clear, and exact description.

10 This invention relates to rotary engines and has reference more particularly to a rotary engine of the internal combustion type in which the power developed by the motive fluid is rendered effective through a turbine element.

The invention also relates to a rotary engine in which is combined a turbine element with a motive fluid chamber of variable capacity for compressing the motive fluid 20 prior to its expansion when exploded and utilized in the turbine element.

The invention further relates to the combination in a rotary engine, of a telescopic member, means for guiding the member in 25 a rotary path, and a turbine for utilizing an explosive mixture compressed by said telescopic member.

More specifically the invention relates to a rotary engine having a main rotor provided with a motive fluid chamber, a secondary rotor movable with the main rotor and eccentric with respect thereto, so as to vary 30 the capacity of the motive fluid chamber and adapt the same for use as a compression chamber, and a turbine element adapted to receive motive fluid under compression from the motive fluid chamber.

An object of the invention is to provide 40 a simple and efficient rotary engine which is in effect a turbine, which is compact in form and light in weight, by means of which the energy of the motive fluid is utilized as completely as possible, in which the expansive force of the motive fluid is rendered 45 fully effective, which may comprise one or more units operating simultaneously, and if so desired, constituting successive stages for multiple expansion, and in which each unit can be provided with a number of working 50 chambers in which the cycles of operation are successively carried out.

A further object of the invention is to combine in an engine a turbine of any desired or preferred type with a primary and

a secondary rotary member forming together a variable motive fluid chamber adapted to deliver to the turbine fluid under compression, and ready to be exploded so that the expansive force of the motive fluid can then be utilized in the turbine element.

The invention consists in the construction and combination of parts to be more fully described hereinafter and particularly set forth and claimed.

Reference is to be had to the accompanying drawings forming a part of this specification, in which similar characters of reference indicate corresponding parts in all the views, and in which—

Figure 1 is a vertical longitudinal section 70 of an engine constituting an embodiment of my invention; and Fig. 2 is a transverse vertical section of the engine.

Before proceeding to a more detailed explanation of my invention, it should be 75 clearly understood that the present form of the device constitutes a modification of or an improvement upon the types of engines disclosed in my co-pending applications for Letters Patent of the United States, filed 80 October 10, 1912, Serial No. 724,955. As in the constructions there disclosed, the present embodiment of my invention includes two relatively movable rotary elements which constitute a variable motive fluid chamber 85 into which the hydrocarbon gas and air-mixture is drawn and then compressed to be delivered when ready for ignition, to a turbine element in which the force developed by the motive fluid is utilized, the turbine 90 element of course being likewise a rotary member and adapted for transmitting its power directly or indirectly to a suitable point of utilization.

While the engine is preferably designed 95 for use as an internal combustion motor, gas, steam, air or other fluid under pressure can be utilized therein as will be readily understood.

In the present application, I have illustrated but one construction embodying the relatively movable members which form the variable motive fluid chamber, but in their place may be employed for example any one of the others illustrated in my co-pending 100 application referred to, or any one adapted for the purpose not shown therein. Similarly, while I have illustrated a spiral tur- 105

bine, any other form of this prime mover may be utilized.

The present form of the engine may be termed a "single-stage" engine, although it combines two separate units, each of which is practically independent of the other. Should it be desired, however, two or more units may be coupled in such a manner that the motor is a multiple expansion engine, and the unit or units after the first one utilize exhaust motive fluid.

Referring more particularly to the drawings, I have shown a form of my invention comprising a suitable base 10 having separated upwardly extending abutments 11 between which is received and mounted a substantially circular engine casing. Resting upon the abutments are respectively two substantially circular casing heads 12 and 13. Disposed between the casing heads and movably associated therewith are two substantially semi-circular elements 14 and 15 having the edges movably and guidingly received in peripheral inner grooves or recesses 16 and 17 of the casing heads 12 and 13. The casing head 12 has a central, inwardly disposed annular extension 18 receiving a bearing collar 19 and constituting a bearing for the spindle end 20 of an exhaust cylinder 21 concentric with the axis of the engine. The opposite end of the exhaust cylinder has mounted thereon a bearing collar 22 received in a central bearing 23 of the casing head 13, the bearing 23 being formed within a circular outward extension of the head. The latter has an outlet opening 24 which communicates with the interior of the cylinder 21. From the opening 24 the exhaust gases are suitably conducted from the engine by means of an exhaust conduit or pipe 25.

As in the form of the engine shown in Fig. 9 of my co-pending application previously referred to, in the present device the main rotor, mounted within the cylindrical casing 14-15 consists of a plurality of unconnected relatively movable partitions 26 arranged axially within the casing and having laterally disposed flanges 27 and 28, the latter considerably less in transverse dimension than the former. The flanges 27 have the outer faces rounded and are in close sliding contact with the inner surface of the cylindrical casing. The flanges 28 on the other hand are in similar engagement with the outer surface of a turbine cylinder 29 arranged concentrically within the engine casing about the exhaust cylinder 21. The turbine cylinder is, like the casing heads 12 and 13, fixed, and does not turn as will be pointed out hereinafter. The secondary rotor consists of a number of members 30 of arcuate cross section arranged substantially axially within the casing between adjacent partitions 26. The said members are inter-

connected at their ends by a circular portion 30' integrally therewith and provided on its outer periphery with teeth 62, thereby forming at each end of said members 30 a gear meshing with a corresponding interior gear 61, provided in the semi-circular elements 14 and 15. The members have at the ends rounded extensions 31 in contact with rounded bearing strips 32, each engaging one of the partitions 26. The circular portions 30' of the members 30 are received in eccentrically disposed guide grooves 33 of the casing head 13 and an annular wall 35 arranged within the casing 14-15 and spaced inwardly from the casing head 12. As the rotors revolve the members 30 move inwardly and outwardly in substantially radial directions owing to the fact that the guide grooves are eccentric with respect to the axis of the casing. The partitions move toward or away from each other as the members 30 alter their positions, so that in this way the effective capacities of the working chambers formed between the adjacent partitions, the members 30 and the turbine cylinder, are varied. These changes in the effective capacities are utilized for drawing in the motive fluid charges and compressing the same as will be pointed out hereinafter.

While I have described the main and secondary rotary elements respectively in the singular, it will be noted that the present form of engine provides two sets of the same spaced by a central radially extended partition 34 of the turbine cylinder 29, this partition extending to and engaging the inner wall of the casing 14-15.

The cylinder spindle 20 between the wall 35 and the bearing 18 has a pinion 36 integral therewith or rigidly secured thereto. This pinion is in mesh with a pair of gears 37 each mounted upon a stub shaft 38. These stub shafts have threaded parts 39 received in correspondingly threaded openings of bosses 40 of the casing head 12. The other ends of the stub shafts 38 are reduced and received in bearing openings 41 of the wall 35. The casing 14-15 is provided with internal gear teeth 42 near the edge thereof adjacent to the casing head 12. These gear teeth are in mesh with the gears 37, so that the casing cylinder is rotated as the gears 37 turn. Mounted upon the casing cylinder 14-15 is a belt band 43 having peripheral radial flanges 44 to prevent lateral displacement of the belt. It will be understood that the power is delivered by the engine from the rotating cylinder casing 14, and this power is transmitted by means of a belt to a point of utilization. Needless to say, the power may be taken from the rotating element in any other suitable manner. Adjacent to the belt band 43, the casing cylinder has a retaining ring 45 in juxtaposition with the belt and tending to hold the same in po-

sition against displacement in one direction. The casing head 12 has a central boss 46 having a threaded opening in which is received an adjustable thrust bearing 47 having a rounded head 48 in contact with the corresponding rounded end of the cylinder spindle 20.

Mounted upon the exhaust cylinder 21 by means of central openings are turbine heads 49 and 50 together with a central wall 51 disposed between the same. The heads 49 and 50 and the wall 51 extend radially from the exhaust cylinder to and into engagement with the inner surface of the turbine cylinder 29. They have at their inner opposite faces grooves 52 spirally disposed and receiving and holding the correspondingly arranged turbine spiral 53. The latter extends from a series of turbine inlet nozzles 54 to the outlet openings 55 of the exhaust cylinder. Adjacent to the inlet nozzles 54, the turbine cylinder has a suitable igniting device 56 consisting of spark plugs included in a suitable electric circuit, or any other means adapted for the purpose. The inlet nozzles 54 of the turbine cylinder which remains fixed are successively in communication with the working chambers formed by the rotating elements. The casing head 13 has an annular extension 57 in which is an annular inlet passage 58 communicating with an inlet conduit 59 which serves to conduct a fuel mixture to the motor. The turbine cylinder 29 has a plurality of axial passages 60 there-in which communicate with the passage 58 through openings 61 of the head 13. The passages 60 lead to and communicate with the working chambers of the rotary elements and serve to permit these to draw into them a charge, compress the same and deliver it to the turbine inlets immediately after ignition of the charge by the device 56. The exploded gases then rush into the turbine, expanding within the spiral and causing the same to rotate, as will be readily understood. The rotation of the turbine is transmitted through the pinion 36 and the gears 37, which in turn drive the rotatable cylindrical casing 14—15 as has already been described.

The above described engine is started by simply giving to the casing 14 and 15 a rotary movement. This rotary movement will cause the rotation of the members 30 through 55 the medium of the engagement of the teeth 62 of said members with the inner gearing 61, whereby the gas drawn through the passages 60 enters into the working chambers and exploded at the proper moment, thereby

60 starting the engine.

It should be noted that preferably the two separate turbine elements and their related parts are so arranged that the ignited charges are delivered thereto at opposite points of the motive cycles in order to bal-

ance the operation of the engine. Should it be desired furthermore, a greater number of turbine elements may be employed.

The present form of rotary engine is cooled in the same way as those described in my co-pending application. In other words, the cooling liquid is introduced between the relatively eccentric rotary members, in the spaces other than those comprising the motive fluid chambers. Suitable means are of course provided (not shown), for the introduction of the water or other fluid.

Having thus described my invention, I claim as new and desire to secure by Letters Patent:

1. In a rotary engine in combination, a stator; a rotor about the stator including means forming a motive fluid chamber of variable capacity intermediate said rotor and stator; and a turbine element within the stator communicating with said chamber.

2. In a rotary engine in combination, a stator; a rotor associated with said stator including means forming with said stator a motive fluid chamber; and a turbine element within the stator and adapted to communicate with said chamber intermittently.

3. In a rotary engine, a rotary casing; a stator concentric with said casing, movable members intermediate said stator and casing and dividing the space therebetween into a series of chambers; a rotor intermediate said stator and casing engaging said movable members, said rotor dividing said chambers into cooling and working chambers, said working chambers being positioned intermediate the rotor and the stator; said rotor having an eccentric path of movement with respect to that of said stator and whereby the capacity of said chambers formed by the rotor with the stator and the casing is varied; a rotary turbine element within said stator, said stator having means establishing communication between said working chambers and said turbine element, when said chambers are at substantially minimum capacity; means for introducing motive fluid into the working chambers; means for exhausting the fluid from the turbine; gearing connecting the turbine element with the casing; and gearing, connecting the casing with the rotor.

4. In a rotary engine, a stator; a rotary casing about said stator including means for forming a chamber therebetween; a member associated with the casing and dividing said chamber into a cooling and working chamber, said rotary casing having means for guiding the movement of said member, whereby the capacity of said working and cooling chamber is varied; and a turbine element within said stator and adapted to communicate with said working chamber at predetermined intervals.

5. In a rotary engine, a stator; a rotary casing about said stator including means forming a constant chamber therebetween; a member within said chamber adapted to move in a predetermined curved path and dividing said constant chamber into a working and a cooling chamber of variable capacity, the working chamber being at the stator and a turbine element within said stator adapted to communicate with said working chamber when the same is at substantially minimum capacity. 70
6. In a rotary engine in combination, a stator, a rotor associated with the stator including means forming with the stator a motive fluid chamber; a revolute casing concentric with said stator and inclosing said rotor and stator, said casing having guiding means therein engaged by said rotor and whereby the capacity of said motive fluid chamber is varied; a turbine element within said stator adapted to communicate with said chamber intermittently, and means for transmitting rotary movement from said turbine element to said casing. 75
7. In a rotary engine in combination, a stator; a rotor associated with said stator including means whereby a series of motive fluid chambers is formed between said rotor and stator; a rotary casing inclosing said rotor and stator and having guiding means for said rotor, whereby the capacity of said motive fluid chambers is varied; a turbine element associated with said stator and adapted to communicate with each of said chambers intermittently; and means for transmitting the rotary movement from said turbine element to said casing and said casing to said rotor. 80
8. In a rotary engine in combination, a stator, a rotor about said stator including means forming with the stator a series of motive fluid chambers; a revolute casing inclosing said rotor and stator and having guiding means engaging said rotor, whereby the capacity of said motive fluid chambers is varied; a turbine element associated with said stator, said stator having means establishing communication between said motive fluid chambers and said turbine element at predetermined intervals, whereby said turbine element is rotated; means for transmitting the rotary movement of the turbine element to said casing; and means transmitting the rotary movement from said casing to the rotor. 105
9. In a rotary engine in combination, a rotary casing; a rotor having an eccentric path with respect to said casing; a stator concentric with said casing; means carried by the rotor and engaging said stator and casing and forming between said rotor and stator variable motive fluid chambers; a rotary turbine element positioned in said stator and constituting the driving element of the engine; said turbine element communicating with said variable motive fluid chambers; and an operative connection between said turbine element, rotary casing and rotor substantially as and for the purpose set forth. 110
10. In a rotary engine in combination, a rotatable casing; a rotor mounted therein; a stator associated with the rotor; means associated with the rotor and stator and forming therewith a series of motive fluid chambers, said casing having means for guiding the movement of said rotor, whereby the capacity of said motive fluid chambers is varied; and a rotary turbine element within said stator and in communication successively with said motive fluid chambers. 115
11. A rotary engine comprising a casing, a rotor mounted therein, to move eccentrically with respect to said casing; a stator within said rotor and concentric with said casing; movable means positioned intermediate said stator and casing and engaged by said rotor, whereby a series of motive fluid chambers of variable capacities is formed intermediate said stator and rotor; a turbine element within said stator having means establishing communication between the turbine element and said chambers at predetermined intervals, and whereby said turbine is rotated; and means for transmitting the rotary movement from said turbine to said rotor. 120
12. A rotary engine comprising a casing, a rotor within said casing; a stator within said rotor concentric with said casing; movable elements positioned intermediate said stator and casing and engaged by said rotor to move thereon, said elements dividing the space intermediate said rotor and stator into a series of motive fluid chambers, said casing having guided means for said rotor, whereby said rotor moves eccentric relatively to said stator and thereby varies the capacity of said motive fluid chambers; a turbine element within said stator, said stator having means establishing connection between said chambers and turbine at predetermined intervals, whereby said turbine element is guided; an operative connection from said turbine to said casing; and an operative connection from said casing to said rotor. 125
13. A rotary engine comprising a rotatable casing; a rotor within said casing; a stator within said rotor and concentric with said casing; movable elements intermediate the stator and the casing engaged by the rotor and adapted to move therewith, said elements dividing the space intermediate the rotor and the stator into a series of motive fluid chambers, said casing having a circular groove eccentric with the axis of said casing engaged by said rotor, whereby dur- 130

- ing the movement of said rotor the capacity of said motive fluid chambers is varied; a turbine element within said stator adapted to receive charges from said chambers where 5 they are substantially at their minimum capacity; means for transmitting the rotary motion from the turbine to the casing; and means for transmitting the rotary movement from the casing to the rotor.
16. 14. An engine having a rotatable casing; a rotor therein having relatively eccentric paths of rotation; a stator associated with the rotor and concentric with the casing; movable members intermediate the casing 15 and stator engaged by the rotor and adapted to move therewith, said members dividing the space intermediate the rotor and casing into cooling chambers and intermediate the rotor and stator into working chambers; a 20 turbine element within said rotor adapted to receive the charges of the working chambers; and operative means connecting said turbine with the casing and said casing with the rotor.
25. 15. In a rotary engine in combination, a ro-
- tary casing; a rotor therein having an eccentric path with respect to said casing; a stator within the rotor concentric with the casing, said rotor having means engaging said casing and stator and forming intermediate said 30 rotor and stator a series of variable motive fluid chambers; a rotary turbine element associated with the stator constituting the driving element of the engine and in communication with said varied motive fluid 35 chambers at predetermined intervals; gearing connecting said turbine element and said casing; gearing connecting said casing and said rotor; means for introducing motive fluid into said variable motive fluid chambers; and means for exhausting the fluid 40 from said turbine.

In testimony whereof I have signed my name to this specification in the presence of two subscribing witnesses.

GUSTAV PROCHAZKA.
